UNITED STATES PATENT OFFICE.

JAMES J. BAJDA, OF FLUSHING, NEW YORK.

CONDENSER.

1,317,262.

Specification of Letters Patent. Patented Sept. 30, 1919.

Application filed June 25, 1918. Serial No. 241,729.

To all whom it may concern:

Be it known that I, JAMES J. BAJDA, a citizen of the United States, residing at Flushing, Long Island, county of Queens, 5 and State of New York, have invented certain new and useful Improvements in Condensers, of which the following is a specification.

The invention relates to a condenser of 10 general application and specifically relates to a glass reflux condenser which can be secured by means of an air-tight connection with the supporting receiver.

The primary object of the invention is to 15 provide a simple and inexpensive form of condenser which will quickly and economically condense the hot vapors received therein and with the least possible destructive action upon the condenser when made of 20 frangible material.

In devices of this character it is usual to admit the hot gases at the relatively cold portion of the cooling chamber and to allow the condensed liquid to collect in the 25 inner tube until overbalancing pressures therein cause the liquid to spurt back into the receiver. This spouting of relatively cool liquid against the hot sides of the condenser tends to rupture the same especially 30 where these devices were made of glass or similar frangible material.

The invention contemplates a construction which contains an adapter designed to be inserted in the stopper of the receiver and 35 so designed that the hot gases from the receiver are conducted from the adapter exteriorly of the cooling chamber and into an inner condensing tube at the relatively hot portion of the cooling chamber. The invention also contemplates the installation of 40 a liquid trap between the condensing tube and the receiver which trap is open to the external air pressure through a feed tube shut off from the receiver by means of the 45 trap.

Various other objects and advantages of the invention will be in part obvious from an inspection of the accompanying drawings and in part will be more fully set forth 50 in the following particular description of one form of mechanism embodying my invention, and the invention also consists in certain new and novel features of construction and combination of parts hereinafter 55 set forth and claimed.

Referring to the accompanying drawing:

The figure is a view in vertical section of the upper portion of a receiver, showing a preferred embodiment of the invention attached thereto and with the cooling chamber and adapter shown in section axially thereof.

In the drawings, there is shown the upper portion 10 of a receiver which may be the usual boiling flask employed in laboratory 65 condensing operations. The receiver is fitted with a stopper 11 in which is supported the condenser constituting the subject-matter of this invention.

The condenser includes a relatively large 70 jacket 12, the lower portion of which is reduced to form a tubular adapter 13 fitted within the stopper 11. The jacket has a closed upper end 14 and the adapter is constricted at the junction of the jacket there- 75 with by means of an inner tube centering ring 15 for a purpose hereinafter described. This ring defines the lower end of a water cooling chamber 16 positioned above the adapter 13. The cooling chamber is pro- 80 vided with a cold water intake nipple 17 and a warmed water discharging nipple 18 as is usual in devices of this character.

The condenser is provided with an inner tube 19, the upper portion of which constitutes a bifurcated Y-tube 20. One arm of this Y-tube leads upwardly and axially through the cooling chamber and through the upper end 14 to form a feed tube 21. The upper end of this feed tube is enlarged 90 to form a funnel 22 by means of which liquid may be introduced through the condenser and into the receiver 10. The other bifurcation of the Y-tube constitutes a condenser tube and in the illustrated device is 95 in the form of a coil 23, the upper end of which leads out through the top 14 of the cooling chamber. This upper end of the coil is connected to the tubular adapter 13 by means of a by-pass pipe 24 positioned 100 exteriorly of the cooling chamber and co-acting with the adapter to constitute a hot gas conduit from the receiver 10 to the upper or relatively hot end of the coil 23. The stem of the Y-tube is bent back twice 105 upon itself to form an S-shaped liquid trap 25. The discharge end of the trap leads through the centering ring 15 and through the adapter 13 to constitute a drip tube 26 adapted to lead the condensates from the 110 trap through the adapter and stopper 11 back into the receiver 10.

In operation and assuming that cold water is passing through the cooling chamber as indicated by the arrows, it will be understood that the lower portion of the 5 cooling chamber is at lower temperatures than the upper portion. The gases generated in the receiver pass through the gas conduit formed by the adapter 13 and bypass 24 and are led therefrom into the upper 10 end of the condenser tube or coil. The vapors are condensed in the coil and the condensates flow into the trap 25 eventually filling the U of the trap as indicated in the drawings. Any high gas pressure in the 15 gas conduit will merely have a tendency to disturb the balanced relation of the condensed liquid in the trap but this trap will at all times shut off the outside air from the receiver, for atmospheric pressure will 20 be maintained on the trap through the open feed tube 21.

This feed tube may also be utilized to replenish the liquid in the receiver and facilitates a quiet flow of liquid from the trap 25 into the receiver.

By means of a device of this character there is provided a compact arrangement which can be supported on a receiver. The gases receive an initial air cooling before 30 they are passed into the liquid cooled coil, thus attaining an accelerated cooling action while economizing in the use of water, ice or other refrigerant passed through the cooling chamber. As the hot gases are introduced 35 at the top of the cooling chamber the cooling of the condensates is gradual and sudden temperature changes are minimized.

The device lends itself readily to glass blowing operations so that it can be formed 40 conveniently and economically.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. A condenser including an upstanding cooling chamber provided with a cooling water inlet adjacent its lower end and a discharging water outlet adjacent its upper end, an inner Y-tube positioned in said chamber, the stem portion of the Y-tube being bent back twice upon itself to form an S-trap, one arm of said Y-tube being in the form of a coil having an intake end adjacent the upper end of the cooling chamber and the other arm opening through the top of the cooling chamber to pass liquid into the trap.

2. A reflux condenser including an upstanding jacket forming a cooling chamber and having its lower end reduced to form a tubular adapter, a gas conduit for placing said tubular adapter in fluid communication with the upper end of the cooling chamber, 70 a cooling coil positioned in said chamber with the upper end of the coil open to the discharge end of the conduit and a trap having its intake end open to the lower end of the coil and having its discharge end extending through the tubular adapter. 75

3. A reflux condenser including an upstanding jacket forming a cooling chamber and having its lower end reduced to form a tubular adapter, a gas conduit for placing 80 said tubular adapter in fluid communication with the upper portion of the cooling chamber, a cooling coil positioned in said chamber with the upper end of the coil open to the discharge end of the conduit and a trap having its intake end open to the lower 85 end of the coil and having its discharge end extending through the tubular adapter and a feed tube for supplying the trap from the exterior of the cooling chamber. 90

4. In a condenser, the combination with a gas circuit comprising in order, a hot-gas-receiving conduit, a cooling coil, a trap and a return drip tube, of a cooling chamber limited to inclose the coil and trap and 95 means providing access to the trap to fill the same from the outside of the cooling chamber.

5. In a reflux condenser, the combination of a cooling chamber, a condenser tube positioned in said chamber, a trap at the discharging end of said condenser tube, a return drip tube leading from said trap and a tube providing access to the receiving end of the trap whereby fluids may be introduced 100 into the return drip tube through the trap. 105

6. In a condenser provided with an adapter of relatively small cross-section adapted to fit in a flask and a cooling chamber above the adapter and of relatively large cross-section, means for introducing cool water to the cooling chamber, a condenser tube in the cooling chamber, a hot gas conduit positioned exteriorly of the cooling 110 chamber leading from the adapter and discharging through the upper portion of the cooling chamber into the upper portion of the condenser tube. 115

7. In a condenser, the combination with 120 an adapter and a cooling chamber positioned above the same, of a bifurcated tube in said chamber and having a discharge end leading through said adapter, one of said bifurcations opened to the outside of the cooling 125 chamber to constitute a feed tube and the other bifurcation constituting a condenser tube having its intake end adjacent the up-

per portion of the cooling chamber and means for leading the hot gases from the adapter to said intake end.

8. In a condenser, the combination with 5 an adapter having a cooling chamber positioned above the same, a bifurcated tube in said chamber and having a discharge end leading through said adapter, one of said bifurcations opened to the outside of the 10 cooling chamber to constitute a feed tube and the other bifurcation constituting a condenser tube having its intake end adjacent the upper portion of the cooling chamber and a liquid trap positioned between the 15 condenser tube and the adapter.
9. In a condenser, the combination with 20 an adapter, a cooling chamber positioned above the same, of a bifurcated tube in said chamber, having a discharge end leading through said adapter, one of said bifurcations opened to the outside of the cooling chamber to constitute a feed tube and the other bifurcation constituting a condenser tube having its intake end adjacent the upper 25 portion of the cooling chamber, a liquid trap positioned between the condenser and

the adapter and an air cooled by-pass pipe leading to the intake end of the condenser tube.

10. In a device of the class described, the 30 combination of two spaced apart tubular members, one of said members constituting a cooling chamber provided with a tubular extension designed to constitute an adapter, a cooling tube mounted in said cooling 35 chamber and in fluid communication with the other tubular member, said tubular-extension constituting a means for supplying hot gases to said other tubular member and means for conducting condensates from said 40 cooling tube through said tubular extension.

11. In a device of the class described, a 45 tubular insert including a cooling coil, a liquid receiving trap at the lower end of said coil, a drip tube leading from the discharge end of said trap, and a feed tube leading to the intake end of said trap.

Signed at Ridgefield Park, in the county of Bergen and State of New Jersey, this 22d day of June, A. D. 1918.

JAMES J. BAJDA.
